APPARATUS FOR THE CONTROL OF
RAILWAY TRAIN BRAKES

Lee Devol, Forest Hills, Pa., and Austin M. Cravath, Berkeley, Calif., assignors to the Union Switch & Signal Company, Swissvale, Pa., a corporation of Pennsylvania

Application January 17, 1935, Serial No. 2,160

11 Claims. (Cl. 246—63)

Our invention relates to apparatus for the control of railway train brakes, and particularly to apparatus for the control of railway train brakes in which the functions of the usual engineer's 5 brake valve on the locomotive are reproduced by an auxiliary brake controlling mechanism located at another point on the train.

One feature of our invention is the provision 10 of apparatus for the control of railway train brakes which includes two synchronized rotating elements, one of which is located on the locomotive and the other at the location of the auxiliary brake controlling mechanism. Other features and advantages of our invention will appear 15 as the specification progresses.

We will describe certain forms of apparatus embodying our invention, and will then point out the novel features thereof in claims.

In the accompanying drawings, Figs. 1 and 2 20 are diagrammatic views of one form of apparatus embodying our invention, Fig. 1 representing that portion of the apparatus located on the locomotive and Fig. 2 representing that portion of the apparatus located at the location of the auxiliary brake controlling mechanism. For the 25 sake of illustration, the location of the auxiliary brake controlling mechanism will be referred to in this description as the caboose of a freight train. Fig. 3 is a diagrammatic view of the rotating element of Fig. 2, and Figs. 4 and 5 are 30 sectional views of Fig. 3. Figs. 6 and 7 are detail views of certain decoding contact mechanism of the apparatus of Fig. 1. Figs. 8 and 9 are diagrammatic views of a second form of apparatus 35 embodying our invention, Fig. 8 representing that portion of the apparatus located on the locomotive and Fig. 9 representing that portion of apparatus located at the auxiliary brake controlling mechanism. Fig. 10 is a diagrammatic view 40 of the accelerating and decelerating mechanism for synchronizing the rotor element of Fig. 9. In each of the several views like reference characters designate similar parts.

Referring first to Figs. 2 and 3 of the caboose 45 apparatus, a shaft 10 is operatively connected with a motor M, as shown schematically by a dotted line, the connection between the motor M and the shaft 10 including a suitable gear train not shown. A tube 11 surrounds the shaft 10 and is made to rotate with the shaft in a manner to shortly appear. Discs a₁, a₂, . . . a₆ are rigidly mounted on the tube 11 for rotation therewith and these discs together with the tube 11 will be referred to hereinafter as a rotor element R.E. 50 A bevel gear 12 and a disc 13 are also attached to

the tube 11 in any convenient manner. A disc 14 is keyed to the shaft 10, and the two discs 13 and 14 constitute a driving clutch for the rotor element R.E., the two discs 13 and 14 being forced into frictional engagement through the medium of a spring 15 placed under tension between the end of the tube 11 and a shoulder 16 on the shaft 10 as shown at the left-hand end of Fig. 3. The disc 14 is preferably cut away so that it makes contact with the disc 13 only near the rim. The gear 12 carries on its surface opposite the gear teeth, a stop 17 which can pass a catch 18 only when the catch is drawn back, that is, drawn to the right in Fig. 3. The catch 18 is pivotally mounted at 19 to a fixed support (not shown) and is biased by a spring 20 to the left to the position for engaging the stop 17, the parts being so proportioned that the catch 18 when forced to its extreme left-hand position just clears the gear 12.

A link member 21 has one end pinned to the 20 lower end of the catch 18 and its other end pinned to a bar member 22, the latter being mounted on convenient guides, not shown, for endwise movement in a plane parallel with the shaft 10. It follows that the spring 20 functions to bias the 25 catch 18 and the bar 22 to the left in the drawing, the extreme left-hand position being determined by a stop 23, the parts being so adjusted that in the left-hand position the catch 18 just clears the gear 12 as stated above. The bar member 22 is preferably of non-magnetizable material and has riveted thereon a magnetizable armature 24 in magnetic relation with an electromagnet 25. It is clear that in energizing the magnet 25 to attract the armature 24 toward its 30 pole pieces 26 and 27, the member 22 and the catch 18 are drawn to the right against the force of the spring 20 to a right-hand position where the catch 18 is out of engagement with the stop 17. When the magnet 25 is deenergized, the catch 40 18 and the member 22 are forced back to the left-hand position due to the force of the spring 20. The surface 17^b of the stop 17 is made slanting so that engagement of the catch 18 with the stop 45 17 forces the gear 12 and the tube 11 to the left to relieve the pressure between the two discs 13 and 14 and reduce the driving torque. In this connection it will be noted that the gear 12 meshes with a pinion 28 to be referred to later with such clearance that endwise motion of gear 50 12 to the left sufficient to disengage the two discs 13 and 14 will be permitted. Consequently, during each revolution of the gear 12, the reception of a synchronizing impulse to energize the magnet 25 at the point where the stop 17 engages the 55

- catch 18, draws the catch 18 out of engagement and rotation of the rotor RE is not obstructed. This impulse need be no longer than the period required for the stop 17 to pass the catch 18.
- 5 If no such synchronizing impulse is received, engagement of the stop 17 and the catch 18 forces the clutch discs 13 and 14 apart and rotation of the rotor RE is stopped. If the impulse is relatively short compared with the regular length of
- 10 a synchronizing impulse, that is, it is not a synchronizing impulse, the catch 18 drops back before a second ridge 17a of the stop 17 has passed, and thus stops rotation of the rotor RE. In the event an impulse ceases just after the stop 17 reaches the position of the catch 18, the catch 18 drops back on the slanting surface 17b, stops the rotor RE and forces it back to the position corresponding to the start of a synchronizing impulse. If a synchronizing impulse is already
- 15 coming in when the stop 17 first comes under the catch 18, the catch 18 drops on the center portion of 17 and stops rotation of the rotor RE as before pointed out, except in the case of a synchronizing impulse which starts just a little before the stop 17 arrives at the catch. In this latter case, the catch 18 falls on the rear sloping surface 17c of the stop 17, disengages the discs 13 and 14, and kicks the rotor RE ahead into synchronism. It follows that reception of a synchronizing impulse of the proper length and at the proper time is effective to draw the catch 18 out of the way and rotation of the rotor RE is not molested. If the rotor RE is ahead of the synchronizing impulse, the stop 17 engages the
- 20 catch 18 and rotation of the rotor is held back until reception of the impulse. If the rotor is behind the impulse only a little the catch falls back on the rear sloping surface 17c of the stop to kick the rotor ahead into synchronism. If the impulse is relatively short, the rotor is stopped and held in check until reception of a second impulse. If the second impulse is also a short impulse, the stop 17 escapes, but the rotor is again held up one revolution later.
- 25 45 As shown more clearly in Figs. 2 and 5, the stop 17 engages a contact spring ds each revolution and forces the spring ds into engagement with a stationary contact gs to complete a circuit connection therethrough. In other words, the contact ds—gs is normally open and is closed once each revolution of the rotor, the period during which it is closed being equal to the time required for the stop 17 to pass under the spring ds. The functions of this synchronizing contact ds—gs will appear later.
- 30 50 55 A speed governor SG is provided which operates electrical contacts 29 and 30 to give an alarm when the speed of rotation of the rotor RE drops to an unusually low value, say to about 70 per cent of the normal speed. As here shown, the governor SG is of the flyball type and is driven by the pinion 28 which meshes with the gear 12. In order to avoid shock when the gear 12 is suddenly stopped, the governor has a friction drive. Pinion 28 is free to rotate on the shaft 31 and is pressed against a collar 32 by a spring 33 which surrounds the shaft 31 between the gear 28 and a collar 34, the two collars 32 and 34 being fixed on the shaft. The governor SG is biased by a spring 33a to the position illustrated in Fig. 3 where a contact member 35 is in engagement with a stationary contact 30. The parts are so proportioned that at normal speed, the contact member
- 75 35 is drawn downward against the force of the

spring 33a to make engagement with the stationary contact 29. At a speed below a given per cent of the normal speed, say below 70 per cent, the member 35 is moved upward into engagement with the stationary contact 30. The manner of utilizing the contacts 29 and 30 in the control of the mechanism will be described later.

5 In order to take care of any accident which might cause the catch 18 to stick in the withdrawn position, that is, stick in the right-hand position in Fig. 3, a projection 36 is placed on the disc 13 to engage the lower end of the pin 37 extending through the catch 18 and the link 21, see Fig. 5. If the catch 18 remains withdrawn too long after the stop 17 passes, the projection 36 strikes the lower end of the pin 37, the rotor RE is stopped and the governor contact 35 is operated to close the contact 30—35.

10 It is advantageous to have the rotor RE run smoothly at just the right speed instead of having it held back or kicked ahead into synchronism at each revolution. This is accomplished as follows: The left-hand end of the tube 11 is threaded and screws into a member 38. The member 38 has a key which slidably engages a keyway 39 in 15 a tube 40, preventing rotation of the member 38 relative to the tube 40 but permitting longitudinal motion. The tube 40 fits over the shaft 10 and is provided at its left-hand end with an enlarged portion on which teeth 46 are cut to mesh 20 with teeth 47 cut on a collar 10a pinned to the shaft 10 at 10b. An arm 42 is pinned at 44 to a fixed support, not shown, and its free end is forked to engage a collar 43 on the tube 40. A biasing spring 45 draws the arm 42 to the left, 25 with the result that the tube 40 is normally pulled to the left where its teeth 46 engage the teeth 47 on the collar 10a and the tube 40 is made to rotate along with the shaft 10. The arm 42 is in magnetic relationship with an electromagnet 41, 30 the arrangement being such that with the magnet 41 energized the arm 42 is drawn to the right against the force of the spring 45 and the tube 40 is pulled out of engagement with the collar 10a and no longer rotates with the shaft 10. 35 It follows that as long as the magnet 41 is de-energized, the member 40 rotates with shaft 10, but that, with the magnet 41 energized, the shaft 10 rotates without driving the member 40. As shown in Fig. 2, the magnet 41 is provided with 40 a circuit extending from the B terminal of any convenient source of current such as a battery, not shown, over governor contacts 35—36, winding of the magnet 41 and to the opposite terminal C of the current source. Hence, as long as 45 the rotor is up to speed and the governor contact 35—36 is open, the magnet 41 is deenergized and the members 40 and 38 are rotated with the shaft 10. As pointed out hereinbefore, if the rotor RE is slightly too slow or too fast, the rotor is kicked 50 ahead or held back a little each revolution. This synchronizing action screws the member 38 to the left or to the right changing the setting of a contact arm 48 which is operated to the left or to the right along with the member 38 through the medium of a slotted collar 49 on the member 38 and a pin 50 on the arm 48. Hence the synchronizing of the rotor RE to screw the member 38 to the left or to the right is effective to change the 55 setting of the arm 48 on the motor field rheostat 51 and correct the error in the speed of the rotor RE by changing the speed of the driving motor M. In the event the speed is much too different and the rotor is stopped for the period between two 60

synchronizing impulses, the member 38 may be moved too far. With the rotor stopped, however, the governor contact 35-30 is closed, magnet 41 is energized and the tube member 40 is drawn out of engagement with the shaft 10, and the excessive movement of the rheostat arm 48 is avoided. It follows that the speed of the driving motor M is varied to bring the speed of the rotor RE to just the right synchronizing speed if the speed of the rotor is only slightly too slow or too fast, but that, if the speed greatly differs from the proper speed the mechanism for varying the speed of the motor M is rendered ineffective.

Decoding contacts are provided which are closed jointly by the magnet 25 and the rotor RE, and are mechanically held in the closed position during the interval between two control impulses by the rotor. As shown in Fig. 2, a decoding contact *f* is associated with each of the discs, *a*1, *a*2, . . . *a*6. The operation of each of these decoding contacts *f*1, *f*2, . . . *f*6 is the same and it is thought a description of one will suffice for an understanding of all. Referring to Figs. 3 and 4, the member 22, as explained hereinbefore is mounted in guides for endwise motion parallel with the shaft 10 in response to the energizing and deenergizing of the magnet 25, being drawn to the right when the magnet 25 is energized and being forced to the left by the spring 20 when the magnet is deenergized. Referring now to the decoding contact *f*6, a spring member *b*6 is rigidly supported in a position such that its upper end extends slightly past the rim of the disc *a*6 as will be clear from an inspection of Fig. 3. A crosspiece *c*6 is pivotally supported on the member 22 adjoining the disc *a*6. The disc *a*6 is provided with a cam lobe 52 and a slot 53. If the magnet 25 is energized and the member 22 is drawn to the right when the disc *a*6 is in any other position than that shown in Fig. 4, the crosspiece *c*6 moves freely past the disc and nothing happens. However, if an impulse for energizing the magnet 25 occurs when the disc is in the position shown in Fig. 4, the tip of the crosspiece *c*6 is arrested from movement to the right by the cam lobe 52 of the disc *a*6, and the crosspiece *c*6 is turned about its pivot and its lower end presses against the spring member *b*6. The cam lobe 52 and the slot 53 on disc *a*6 are so positioned that rotation of the crosspiece *c*6 in response to its engagement with the cam lobe 52 forces the spring *b*6 through the slot 53 to the right-hand side of the disc *a*6 and into a position where the contact *f*6 is forced into engagement with a mating contact *e*6. By the time such an impulse ceases, the disc *a*6 has turned so that the spring *b*6 cannot return through the slot 53 until the next revolution of the disc and the slot 53 again aligns with the spring. If the same impulse is received each revolution of the disc, the spring *b*6 is held in its right-hand position where it is effective to hold closed the decoding contact *f*6-*e*6. In other words, the contact *f*6-*e*6 is continuously held closed in response to such periodical impulses, since the control impulse is made to over-lap the period during which the spring *b*6 can pass through the slot 53. The remaining decoding contacts *f*1-*f*5 are operated in a similar manner to that just described for the contact *f*6, except for the fact that the cam lobes and slots of the respective discs *a*1, . . . *a*5 are positioned at different points on the circumference of the discs. It is clear from the foregoing that time is divided into units represented by a single revolution of the rotor RE, and the control impulses

are differentiated from each other by the time they must appear as measured from the start of each revolution. These several decoding contacts operated in response to the control impulses energizing the magnet 25 are used for controlling a brake controlling mechanism and a signal device, and for sending out indication impulses as will shortly appear.

A second contact is associated with each of the rotor discs *a*. Referring particularly to Figs. 10 and 4, a contact *d*6 is raised into engagement with a contact *g*6 at such time as the cam lobe 52 of the disc *a*6 passes under the contact *d*6. That is, the contact *d*6-*g*6 is closed for a short period once each revolution of the rotor RE. In like manner the contacts *d*1-*g*1 . . . *d*5-*g*5 are each closed for a period once each revolution of the rotor, but are closed at different points in the revolution.

In railway train brake controlling systems of the type here involved, it has been proposed to transmit control impulses between the location of the control apparatus and the location of the brake controlling mechanism through the medium of either coded or modulated impulses of a carrier current, the traffic rails serving as a part of the communicating channel in the manner disclosed and claimed in the L. O. Grondahl application for United States Letters Patent, Serial No. 450,135, filed May 30, 1930, for Electric train signal systems. To this end the locomotive and the caboose are each equipped with inductor coils effective to induce an electromotive force in the rails in response to a current flowing in the coils and to inductively receive an electromotive force due to current flowing in the rails. In Figs. 2, 6 and 7 are coils mounted on the caboose in inductive relationship with the traffic rails 1 and 1^a, respectively. These coils 6 and 7 are at times connected with an oscillator or generator of carrier frequency current for supplying current to the rails and at other times they are connected with the input of receiving apparatus for receiving such current. Located on the caboose is an oscillator or generator G of carrier current of a frequency of, say 7000 cycles per second. This generator may take different forms, among them being the vacuum tube oscillator type. This generator G is shown conventionally for the sake of simplicity since its specific structure forms no part of our invention. An amplifier detector AD is provided for the receiving apparatus of the caboose and this device may take any of several forms well known to the art, and it is also shown conventionally since its specific structure forms no part of our invention. Suffice it to say, that an impulse of carrier current applied to the input of the amplifier detector AD is amplified and detected and a corresponding direct current signal impulse is caused to appear in its output circuit.

The coils 6 and 7 are normally connected with the input of the device AD by a simple circuit which includes the back contact 54 of a relay T. With the relay T energized, the coils 6 and 7 are transferred from the amplifier detector AD to the output circuit of the generator G, a front contact 55 of the relay T being interposed in the connection. As here shown the generator G is rendered active by the closing of a second front contact 56 of the relay T. It follows that normally the coils 6 and 7 are connected with the amplifier detector AD and are transferred to the generator G by the energizing of the relay T.

T, the generator G being rendered active when the relay is picked up.

A three-pole double-throw switch designated by the reference character S may be mounted on the caboose. The normal position of the switch S is the upper closed position as viewed in Fig. 2, and in this position the output of the amplifier detector AD is connected to the winding of the magnet 25 over the wires 58 and 59. This position of the switch S connects over its contact blade 57 the winding of the relay T with indication circuits or with a synchronizing circuit, all of which circuits will be explained hereinafter. With the switch S operated to its downward closed position, the output of the device AD is connected with a test lamp 60, and the winding of the relay T is connected directly with the positive terminal of the current source over a testing push button 61, the arrangement being such that the relay is energized whenever the push button 61 is depressed.

The caboose is provided with an auxiliary brake controlling mechanism comprising a main reservoir MR, a feed valve FV and a plurality of electropneumatic valves D adapted to reproduce the functions of the usual engineer's brake valve on the locomotive. It will be understood, of course, that the caboose is also equipped with a compressor and all necessary connections to insure an air pressure in the reservoir MR independent of such source of air pressure provided on the locomotive. Valves DC, DR, and DE are each biased to the closed position and each valve is opened when its associated magnet 62 is energized. The valve DS is biased to its open position and is closed when its associated magnet 62 is energized. When the valve DC is open, the main reservoir MR is connected with the brake pipe BP and the auxiliary brake controlling mechanism then represents the condition established on the locomotive when the engineer's valve is in the release position. When the valve DR is open, the brake pipe is connected with the feed valve FV thereby reproducing the condition existing on the locomotive when the engineer's valve is in the running position. When the valve DS is open, that is, when its associated magnet 62 is deenergized, the brake pipe is connected with the atmosphere through a vent of such characteristics as to produce a reduction in brake pipe pressure at substantially the service rate of the usual engineer's valve to effect a service application of the train brakes. When the valve DE is open the brake pipe is connected to the atmosphere through a vent of such characteristics as to produce an emergency rate of reduction of brake pipe pressure, and an emergency application of the train brakes. When all of the valves are held closed both the supply and the exhaust of the brake pipe are blanked, and the condition reproduced by the auxiliary brake mechanism corresponds to the lap position of the engineer's brake valve.

With the rotor element RE of Fig. 2 up to its normal speed and the speed governor contact 35-29 closed, a circuit can be traced from the terminal B of the current source over governor contact 35-29, wire 63, magnet 62 of the valve DS, decoding contact f1-e1, decoding contact f4-e4, assuming these two contacts to be closed in a manner to later appear, magnet 62 of the valve DR and to the opposite terminal C of the current source. It follows that under this condition, namely, the two decoding contacts f1-e1 and f4-e4 are closed, the running position of

the auxiliary brake controlling mechanism is established. Again, in the event the decoding contacts f1-e1 and f2-e2 are closed, a circuit may be traced from the B battery terminal over contact 35-29, wire 63, magnet 62 of the valve DS, decoding contacts f1-e1 and f2-e2, magnet 62 of the valve DE and to the opposite battery terminal C, and the emergency application condition is established for the auxiliary brake mechanism. Again, if the two decoding contacts f1-e1 and f3-e3 are closed, a similar circuit which includes the magnet of the valve DS and the winding of the lap relay 64 is completed and the lap condition of the auxiliary brake mechanism is established. With the two decoding contacts f1-e1 and f5-e5 closed, a circuit is completed which includes the magnets of the two valves DS and DC in series, and the release condition of the auxiliary brake mechanism is established. It is to be noted that a signal bell SB is energized by the closing of the decoding contact f6-e6.

Synchronizing impulses are sent out from the caboose whenever the rotor is up to speed. Still referring to Fig. 2, the closing of the contact ds-gs by the stop 17 in the manner described hereinbefore completes a circuit that can be traced from the B battery terminal over contact 35-29, contact ds-gs, blade 57 of switch S, winding of the relay T and to the opposite terminal C of the current source. Thus, once during each revolution of the rotor RE, the contact ds-gs is closed and the relay T is picked up to supply an impulse of current to the coils 6 and 7 for inducing an electromotive force in the traffic rails. The stop 17 and spring ds are so constructed that this synchronizing impulse is relatively long, and for reasons to appear later this synchronizing impulse is sent out substantially one-half revolution from the point where the stop 17 engages the catch 18.

Indication impulses are sent out from the caboose each revolution of the rotor over contacts operated by the valve mechanism in series with contacts operated by the rotor. To be explicit, when the valve DS is closed and a contact 66 operatively connected to that valve as indicated by a dotted line is closed, the closing of the contact d1-g1 in response to the cam lobe 52 of disc a1 engaging the spring d1, is effective to complete a circuit extending from the B terminal of the current source over contact 35-29, contact d1-g1, wire 65, contact 66 of the valve DS, wire 217, blade 57 of switch S, winding of the relay T and thence to the opposite terminal C of the current source. Thus, during each revolution of the disc a1, the relay T is picked up for an interval and an impulse of current is supplied to the traffic rails if the valve DS is closed. The length of the cam lobe 52 on the disc a1 is so proportioned that the length of this indication impulse is relatively short, that is, relatively short when compared with the synchronizing impulse. In like manner, the closing of the contact d4-g4 associated with the disc a4 completes a circuit for energizing the relay T if the magnet 62 of the valve DR is energized and a contact 67 operated by that valve is closed. This circuit may be traced from the B battery terminal over contact 35-29, contact d4-g4, contact 67, wire 217, switch S, and winding of the relay T to the opposite battery terminal C. Thus, the relay T is picked up and an indication impulse is supplied to the traffic rails once each revolution of the disc a4 as long as the valve DR is held open. Again, the energizing of the magnet 62 for the valve DE and the closing of the

contact 68 operated by that magnet is effective to complete a circuit easily traced that includes the contact d2—g2 and the winding of the relay T. Hence, the relay T is picked up and an indication impulse is supplied to the traffic rails once each revolution of the disc a2 if the valve D^c is open. Energizing the lap relay 64 to close its front contact 69 is effective to close an indication circuit for energizing the relay T and which circuit includes the contact d3—g3. Thus an indication impulse is sent out from the caboose once each revolution of the disc a3 if the lap relay 64 is picked up. When the magnet 62 of the valve D^c is energized and a contact 70 operated thereby is closed, another indication circuit is completed for energizing the relay T, which includes the contact d5—g5, with the result that an indication impulse is sent out each revolution of the disc a5 if the valve D^c is held open. It will be noted that depressing the push button 71 will be effective to complete a circuit for energizing the relay T whenever the contact d6—g6 is closed, and hence signal impulses may be periodically supplied to the traffic rails by the operator depressing the push button 71.

To further check the position of the auxiliary brake controlling mechanism, the caboose is provided with a signal lamp 72 and a bell 73, and additional contacts are added to the several pneumatic valves. In the event the magnets of all the valves are deenergized, except the magnet for the valve D^s, so that the front contact 74 and each of the back contacts 75, 76, 77 and 78 are closed, a circuit is completed from the B battery terminal over these contacts in series, the winding of the bell 73 and to the battery terminal C. Again, in the event the valve D^s is open and its back contact 79 is closed and the magnet of any one of the other valves is energized to close a respective contact, another circuit easily traced is completed for operating the bell 73. With the rotor up to speed and the contact 35—29 closed, the lamp 72 is illuminated by a simple circuit to indicate the proper operating condition of the rotor element. When the speed of the rotor falls below 70 percent of the normal speed, the contact 35—29 is opened and the contact 35—30 is closed, with the result that the lamp 72 is extinguished and the bell 73 is operated.

Referring now to the locomotive apparatus of Fig. 1, a motor driven shaft 80 has rigidly mounted thereon contact operating discs a1 . . . a6, a synchronizing disc as and a gear 12 to form the locomotive rotor element RE¹, with which the caboose rotor element RE is caused to rotate in synchronism. The shaft 88 of the rotor element RE¹ is not equipped with synchronizing mechanism such as described for the shaft 16 of the rotor RE since the locomotive rotor RE¹ is the governing rotor. The shaft 80 is provided, however, with a speed governor SG and is threaded at 81. The decoding contact mechanisms operated by the discs mounted on the shaft 80 are operated by a magnet 88 and a sliding member 283 in a manner similar to that described for the decoding contacts of the caboose apparatus, except that the decoding contact mechanisms of Fig. 1 are provided with more contacts and the synchronizing disc as and contact spring bs are modified. As here shown, the member 283 is biased to the left to the position illustrated in Fig. 1 by a spring 225 and is adapted to be drawn to the right against the force of spring 225 by the magnet 88 when that magnet is energized in the manner to be described later, the magnet being normally

deenergized. Referring to Figs. 6 and 7, a catch 82, which has a ratchet action, has been added to the spring contact bs and the disc as of the rotor RE¹ has been cut away so that when it is in the position shown in Fig. 6, the tip of catch 82 can pass through the extended portion of the slot of the disc. If an impulse arrives and energizes the magnet 88 while the disc is in this position, the magnet 88 is energized for a period sufficiently long for the entire slot of the disc as to pass by the spring bs and, when the impulse ceases, the spring bs is held over to the right since its tip engages the right-hand side of the rim of the disc. In the event the impulse is short, that is, it is not a synchronizing impulse, and the magnet 88 is deenergized before the slot of the disc as has passed by the spring bs, the bias of the spring bs actuates the spring back to the left-hand side of the disc, for although the catch 82 strikes the disc, it is pivoted at 83 and turns so as to slip by the rim of the disc, a spring 84 being effective to return the catch 82 to its normal position. Again, if the impulse arrives a little too late, the catch 82 prevents the spring bs from being actuated. As shown schematically by 30 dotted lines in Fig. 1, the springs b1 . . . b6, each operates a series of contacts, the arrangement being such that with a spring in its biased position, the corresponding back contacts operated thereby are closed, and when the spring is moved 35 to its operating position, that is, to the right-hand position in Fig. 1, the corresponding front contacts operated thereby are closed.

At the right-hand end of the shaft 80 are located a magnet 89 and mechanically operating 40 timing contacts. When the magnet 89 is energized, a lever 90 is held up. This raised position of the lever 90 lifts a contact spring 91 out of engagement with a contact 92, and also disengages a lever 93 from the screw thread 81 formed 45 on the shaft 80. A spring 94 biases the lever 93 to the right where it closes a contact 95. When the magnet 89 is deenergized, the lever 90 drops to close the contact 91—92 immediately and to engage the lever 93 with the screw thread 81. 50 The screw 81 now carries the lever 93 to the left against the biasing force of the spring 94 to open the contact 95 after any desired time interval. The contact 91—92 controls a simple circuit for an indication device here shown in 55 the form of a bell 96. The contact 95 serves as a stick contact for the magnet 89 and also governs the outgoing control impulses in a manner to later appear.

4 and 5 are inductor coils mounted on the locomotive in an inductive relation with the traffic rails 1 and 1^a, respectively. These coils 4 and 5 are connected with the input of the amplifier detector AD over a back contact 86 of a directional relay T¹ and are connected with the 65 output of the locomotive generator G, over a front contact 81 of that relay. The generator G and the amplifier detector AD on the locomotive are preferably similar to the corresponding devices of Fig. 2. The output of the device AD 70 is connected with the winding of the magnet 88, over a manually operated switch S similar to the switch S of the caboose. It follows that the directional relay T¹ of Fig. 1 controls the sending and the receiving of current on the loco- 75

motive in a manner similar to the control of the directional relay T of the caboose.

EV is an engineer's brake valve of any of the standard types, capable of assuming several brake controlling positions, namely, release, running, lap, service and emergency. As shown schematically, a contact member 97 is operatively connected with a handle 3 of the brake valve EV. The member 97 is adapted to engage a contact 98 in all of the positions except the service position, and to engage the contacts 99, 100, 101, 102 and 103 in the release, running, lap, service and emergency positions, respectively. The functions of this contact assembly associated with the brake valve EV will appear when the operation of the apparatus is described.

With the rotor RE₁ up to speed and the governor contact 85 closed, a synchronizing impulse is sent out from the locomotive once each revolution of the rotor element, since the directional relay T₁ is energized for a period to transfer the coils 4 and 5 to the out-put of the generator G. The control circuit for energizing the relay T₁ for sending this synchronizing impulse can be traced from the terminal B of the current source on the locomotive over contact 85, wire 217, contact d₅-g₅ operated by disc a₅, wire 104, winding of the relay T₁, and to the opposite terminal C of the current source. This synchronizing impulse is relatively long as evidenced by the length of the cam lobe 105 (see Fig. 6), provided on the disc a₅. With the rotor RE₁ up to speed and the magnet 89 energized, control impulses are sent out in accordance with the setting of the engineer's brake valve. For example, with handle 3 set at the running position as illustrated in the drawing, current flows from the B battery terminal over contacts 85 and 95, wire 207, contacts 97 and 100 of the contact assembly, code contact d₄-g₄ operated by disc a₄, wire 104, winding of the relay T₁, and to the opposite battery terminal C, and relay T₁ is picked up, with the result that a control impulse is supplied to the traffic rails during the period the code contact d₄-g₄ is closed. This control impulse is relatively short as evidenced by the length of the cam lobe 52 provided on all the discs, except the synchronizing disc a₅. From an analysis of Fig. 1, it is clear that with the handle 3 set in any of its other positions except the service position, a circuit is completed for energizing the relay T₁ over one of the code contacts operated by the several discs of the rotor element. These control impulses are all substantially of the same length which as pointed out above are relatively short impulses as compared with the synchronizing impulses. Under the service position of the handle 3, no circuit is provided for the relay T₁, and hence no control impulse is sent out for this position of the engineer's brake valve.

The different control impulses sent out by the apparatus of Fig. 1 are differentiated from each other by the time they are made to appear from the start of a revolution of the rotor element RE₁. It will be noted in this connection that the cam lobes of the discs of the locomotive rotor RE₁ are preferably located on the different discs so as to successively pass and close the associated control code contacts during the first one-half revolution of the rotors, but that the cam lobes on the caboose rotor RE are located on the respective discs so as to successively close the indication code contacts associated therewith, during the second one-half revolution of the rotors. The

slots cut in the different discs of rotor RE for aligning with the decoding contact mechanisms are cut in the different discs for successively aligning with the respective decoding contact springs during the first one-half rotation of the rotors, and the slots cut in the discs of the rotor RE₁ are so positioned as to successively align with the respective decoding contact springs during the second one-half of a revolution. In other words, the slots of the different discs of the caboose rotor RE appear opposite the associated decoding contact springs approximately the same time as the cam lobes of the corresponding discs of the locomotive rotor RE₁ pass under the respective control code contacts, and in like manner the slots of the different discs of the locomotive rotor RE₁ appear opposite the associated decoding contact springs at approximately the same time as the cam lobes of the different discs of the caboose rotor RE passes over the respective indication code contacts. For example, the control contact d₁-g₁ of the locomotive rotor RE₁ is closed at a predetermined time interval from the starting point of a revolution, and the slot 53 of the disc a₁ of the caboose rotor RE aligns with its spring b₁ at substantially the same predetermined time interval from the starting point of a revolution. Again, the indication code contact d₁-g₁ of the caboose rotor RE is closed at a predetermined time interval during the second one-half of a revolution, and the slot 53 of the disc a₁ of the locomotive rotor RE₁ aligns with its spring b₁ at substantially the same time interval during the second one-half of a revolution. It follows from the foregoing that the control impulses sent out from the locomotive occur during the first one-half revolution of the rotors and the indication impulses returned from the caboose occur during the second one-half of the revolution. The synchronizing impulse sent from the locomotive occurs at approximately the starting point of each revolution and the indication synchronizing impulse sent from the caboose occurs at substantially one-half revolution away from the start.

From Fig. 1, it is clear that with the handle 3 set at any position other than the service position, and the contact member 97 in engagement with the contact 98, the relay T₁ is energized each revolution of the disc a₁ of the rotor and a control impulse is supplied to the rails in addition to the control impulse corresponding to the specific position of the handle 3 as explained hereinbefore. This circuit for relay T₁ includes the B battery terminal, contacts 85 and 95, wire 207, contacts 97 and 98, contact d₁-g₁, wire 104 and winding of relay T₁ to the C battery terminal. Hence, for all positions of the handle 3 except the service position, two control impulses are delivered to the traffic rails each revolution of the rotor, one impulse when the contact d₁-g₁ is closed, and a second impulse when the code contact corresponding to a position of a handle 3 is closed.

As set forth hereinabove, the magnet 89 when energized operates the member 208 to the right and by so doing governs the decoding contacts of the rotor RE₁. The decoding contacts of Fig. 1 are utilized for governing a series of check circuits for the magnet 89, and hence in turn govern the operation of the indication bell 96, and the outgoing control impulses, since the contacts 92 and 95 operated by the magnet 89 are interposed in the circuit for the bell 96, and in the circuit for the relay T₁, respectively. Assuming the apparatus of Fig. 1 is in the position illustrated,

that is, the handle 3 is set in the running position, and the decoding springs b1, b4 and bs are operated to the right-hand position, a check circuit can be traced from the terminal B of the current source over contact 85 of the governor, contact 95 of magnet 89, contact 97-100, wire 106, front contact 107 operated by the spring b1, back contacts 108 and 109 of the springs b2 and b3, respectively, front contact 110 of spring b4, back contact 111 of spring b5, front contact 112 of spring bs, and winding of the magnet 89 to the opposite terminal C of the current source. Thus the magnet 89 is held continuously energized as long as the handle 3 is set in the running position and if the synchronizing decoding contact 112 and the two indication decoding contacts 107 and 110 are closed. In like manner, a similar check circuit for the magnet 89 is provided for each of the other operating positions of the handle 3, as will be understood by an inspection of Fig. 1. It follows, that the magnet 89 is held energized over a check circuit which is closed only when all of the following conditions are simultaneously fulfilled: (a) the rotor is up to speed and the contact 85 is closed; (b) magnet 89 has recently been energized and its contact 95 is closed; (c) the decoding contacts corresponding to the position of the handle 3 are closed; (d) contact 112 of the synchronizing decoding contact spring bs is closed.

In describing the operation of the apparatus of Figs. 1 and 2, we shall assume that the handle 3 is first set at the running position for establishing the running condition of the auxiliary brake controlling mechanism. As soon as the rotor RE1 is up to speed and the contact 85 is closed, a synchronizing impulse will be sent out from the locomotive at the start of each revolution of the rotor, since the circuit for the relay T1 will be completed each time the contact ds-gs is closed. This impulse flows in the traffic rails and will induce a corresponding electromotive force in the coils 6 and 7 mounted on the caboose, with the result that the magnet 25 will be energized and the rotor RE will be quickly brought into synchronism with the rotor RE1. The caboose rotor RE when it is up to speed and its contact ds-gs is closed will be effective to supply a return indication synchronizing impulse once each revolution, and this impulse will flow in the traffic rails and will induce a corresponding electromotive force in the coils 4 and 5 mounted on the locomotive, with the result that the magnet 88 is energized to actuate the decoding spring bs and close its contact 112. In the meantime, the operator on the locomotive will depress the push button 113 and pick up the magnet 89 by a simple local circuit. With the magnet 89 energized a control impulse will be sent from the locomotive during the intervals the contacts d1-g1 and d4-g4 are closed. These control impulses will appear at the caboose at the proper intervals for energizing the magnet 25 to close the decoding contacts f1-e1 and f4-e4, with the result that the circuit for energizing the magnets of the valves D^R and D^S will be completed, and the auxiliary brake controlling mechanism will assume the running position. As soon as the valves D^R and D^S are operated and the contacts 67 and 66 are closed, indication impulses will be returned from the caboose during the intervals the contacts d1-g1 and d4-g4 of the rotor RE are closed. These indication impulses will appear at the locomotive and energize the magnet 88 at the proper intervals for operating the decoding springs b1 and b4. With the decoding springs

b1 and b4 of the locomotive rotor RE1 operated to the right-hand position, the check circuit for the magnet 89 will be completed and that magnet will be held continuously energized as long as the handle 3 remains at the running position. From this point on, a synchronizing impulse will be sent out from the locomotive at the start of each revolution of the rotors, and control impulses will be sent out during the intervals the contacts d1-g1 and d4-g4 of the rotor RE1 are closed in the first one-half of each revolution. An indication synchronizing impulse will be returned from the caboose at the beginning of the second one-half of each revolution, and indication impulses will be returned during the second one-half of the revolution at the intervals the contacts d1-g1 and d4-g4 of the rotor RE are closed. An analysis of Figs. 1 and 2 will disclose that a similar operation will take place for each of the other positions of the handle 3. In each case the control impulses will appear at the proper interval for causing the auxiliary brake controlling mechanism to register with the engineer's brake valve and the return indication impulses will occur at the proper intervals for retaining the magnet 89 of the locomotive apparatus energized. At the service position of the handle 3, however, no control impulse will be sent out from the locomotive and the valve D^S on the caboose will be released for establishing a service application of the train brakes. Under this service condition no return indication impulse will be sent out from the caboose but the magnet 89 on the locomotive will be retained energized since the synchronizing impulses are continued and a circuit for the magnet 89 is provided which includes the back contacts 219, 220, 221, 222 and 111 of the decoding springs b, and the front synchronizing contact 112. To send signaling impulses from the locomotive, the operator will depress the push button 209 for completing a circuit for the relay T1 which includes the contact d6-g6 of the rotor RE1, with the result that a corresponding signaling impulse will be supplied to the traffic rails. This signaling impulse will appear at the caboose and energize the magnet 25 at the proper interval for closing the contact f6-e6 and operate the signal bell SB. For signaling from the caboose, the caboose operator will depress the push button 71 and a signaling impulse will be sent, which will appear at the locomotive at the proper interval for energizing the magnet 88 to operate the spring b6 to close a contact 210 interposed in the circuit for a signal bell 211. It will be noted that with the locomotive rotor RE1 up to speed to close the contact 85 and with the indication magnet 89 energized to close its contact 95, current will be supplied to the magnet 212 of a pneumatic valve 213 which is normally biased to an open position and is held closed when the magnet 212 is supplied with current. Valve 213 when open connects the brake pipe BP to the atmosphere through a vent of such characteristics as to establish a service application of the train brakes. Valve 213 as thus provided checks the operating condition of the locomotive apparatus.

In Fig. 8, the rotor element consists of a motor driven shaft and a set of commutators. As here shown, a motor driven shaft indicated by the dotted line 114 has rigidly mounted thereon four brushes B1, B2, B3 and B4, which are adapted to be driven at a desired speed in a counter-clockwise direction over the stationary segments of the commutators C1, C2, C3 and C4, respectively.

Each particular impulse to be transmitted from the locomotive is sent when these commutator brushes are in a particular position of the first one-half of each revolution, and each particular impulse to be received on the locomotive is picked up when the commutator brushes are in a particular position of the second one-half of each revolution. As will appear hereinafter, during approximately the first one-half of a revolution of the brushes from the position illustrated in the drawings, the locomotive apparatus is conditioned for receiving impulses and during approximately the second one-half of the revolution the locomotive apparatus is conditioned for transmitting impulses. At the position illustrated and just prior thereto the locomotive apparatus transmits a series of synchronizing impulses and just following the position illustrated the locomotive apparatus is in a position to receive a synchronizing impulse.

The locomotive is provided with an oscillator or generator G and an amplifier detector AD preferably similar to the corresponding devices of Fig. 1. The engineer's brake valve EV governs a contact assembly similar to that of Fig. 1. In this instance, the contact member 97 operated by the valve handle 3 is adapted to make engagement with an arcuate contact 119 in all positions of the handle, and to engage with the contacts 120, 121, 122 and 123 in the release, running, lap and emergency positions, respectively.

The inductor coils 4 and 5 for the locomotive of this second form of apparatus are connected by the commutator C1 with the input of the amplifier detector AD during the first one-half of each revolution of the rotor, and are connected with the output of the generator G during the other half of the revolution. As here shown, the coils 4 and 5 are provided with a circuit that extends from the right-hand terminal of the coil 5 over segment 115 of the commutator C1, brush B1, segment 116, input of the device AD and thence to the left-hand terminal of the coil 4, the coils 4 and 5 being connected in series. During the second one-half of the revolution while the brush B1 spans the segments 115 and 117, the coils 4 and 5 are connected with the output of the generator G, the circuit being further controlled by the commutator C2, a relay R1 and the contact assembly for the valve EV. Assuming the relay R1 to be picked up in a manner to later appear and the handle 3 to be set at the running position, a transmitting circuit can be traced from the lower terminal of the generator G through coils 4 and 5, segment 115, brush B1, segment 117 of the commutator C1, segment 118 of the commutator C2, brush B2, segment 124, when the brush B2 has rotated to the position of the segment 124, wire 125, contacts 121, 97 and 119 of the contact assembly, front contact 126 of the relay R1 and to the opposite terminal of the generator G. In a similar manner engagement of the brush B2 with the segments 127, 128 and 129 completes a transmitting circuit for connecting the coils 4 and 5 with the generator G in the emergency, lap and release positions of the handle 3, respectively. It will be noted that during the intervals the brush B2 spans the segments 130 and 131, the coils 4 and 5 are connected with the generator G by a circuit not governed by the contact assembly, but which includes the front contact 126 of the relay R1. Furthermore, during the interval the brush B2 engages the segment 143, the coils 4 and 5 are connected with the generator G by a circuit governed by the commutators C1 and C2 only. It

follows that during the second one-half of each revolution of the rotor, the brush B2 makes contact successively with the different segments of the commutator C2 to connect the coils 4 and 5 to the generator for supplying to the traffic rails a control impulse in accordance with the position of the engineer's brake valve, but that at the beginning of a revolution and at the completion of the revolution, circuits not governed by the contact assembly are completed for supplying to the rails synchronizing impulses.

Lamps LC, LR, LL and LE form indicating devices on the locomotive for indicating the release, running, lap and emergency positions of the auxiliary brake controlling mechanism in the caboose, 15 respectively, the service position being indicated when all the lamps are dark. A signal lamp 134 is also provided. These lamps are successively connected with the output of the amplifier detector AD by the commutator C3. Assuming the 20 brush B3 of the commutator C3 to have advanced to the position where it engages the segment 156, a circuit extends from the lower right-hand terminal of the device AD over segment 136, brush B3, segment 156, lamp LR, winding of 25 a relay 141 and thence to the opposite output terminal of the device AD. A similar circuit is provided for each of the other lamps when the brush B3 spans the segments 216, 215, 214 and 286 as will be readily understood by an inspection of 30 Fig. 8. The relay 141, the winding of which is interposed in the circuit for each of the indication lamps, governs at its front contact 142, a simple circuit for the magnet 212 of the checking brake valve 213 provided on the locomotive. 35 The relay 141 is slow releasing and remains energized from one indication impulse to the next. It follows that the commutator C3 successively connects the indication lamps and the signal lamp 134 with the output of the amplifier detector AD 40 during the first one-half revolution of the rotor, during which period the inductor coils 4 and 5 are connected with the input of the amplifier detector by the commutator C1.

The relay R1 which governs the transmitting 45 of the control impulses from the locomotive is itself controlled by the synchronizing impulses received on the locomotive and by a local source of current in the following manner. During the interval the brush B3 spans the segment 135, the 50 winding of the relay R1 is connected with the output of the device AD by a circuit easily traced. Relay R1 is further provided with a stick circuit for receiving current from the battery 137. Starting from the right-hand terminal of the 55 battery 137 this stick circuit includes the segment 138 of the commutator C4, brush B4, segment 139, winding of the relay R1, its own front contact 140 and thence to the opposite terminal of the battery 137. It will be noted that the 60 segment 138 of the commutator C4 is broken at 202 and hence the relay R1 is released during the interval the brush B4 spans this broken space 202 of the segment 138 unless at the same time an impulse is received from the traffic rails and 65 a corresponding impulse is caused to flow in the output of the device AD over the circuit that includes the segment 135 of commutator C3 and the winding of the relay R1. In other words, with the relay R1 once picked up, it is retained 70 energized by current supplied from battery 137 if a synchronizing impulse is received each revolution of the rotor during the period the stick circuit is ruptured.

The caboose apparatus associated with the 75

locomotive apparatus of Fig. 8 is shown in Fig. 9, and is similar to that provided for the locomotive except for the addition of apparatus by which synchronization is accomplished, and by the fact that the indication lamps are replaced by magnets of the auxiliary brake controlling mechanism. The auxiliary brake controlling mechanism of Fig. 9 is preferably the same as that disclosed in Fig. 2, except that the magnets are made slow releasing in character and a resistance 176 replaces the lap relay 64. It is thought therefore to be unnecessary to repeat its description.

In Fig. 9, the rotor element consists of a motor driven shaft indicated by the dotted line 144 and the brushes of a series of commutators C5, C6, C7, C8 and C9. The respective brushes B5, B6, B7, B8 and B9 are rigidly mounted on the shaft 144 for rotation in a counter-clockwise direction over the commutators C5, C6, C7, C8 and C9, respectively.

That the caboose apparatus will operate in step with the locomotive apparatus, the inductor coils 6 and 7 of Fig. 9 are connected with the output 6 of the associated generator G during the first one-half of a rotation of the rotor, during which period the inductor coils 4 and 5 on the locomotive are connected with the receiving apparatus. During the second one-half of a rotation 30 of the rotor, the coils 6 and 7 are transferred to the input of the associated amplifier detector AD, and at which period the inductor coils 4 and 5 on the locomotive are connected with its generator G. This transfer of the coils 6 and 7 from the 35 sending to the receiving apparatus is controlled by the commutators C6, C7 and C8. Assuming the apparatus of Fig. 9 to occupy the position illustrated, a circuit can be traced from the left-hand terminal of coil 6 over wires 164 and 165, segment 166 of commutator C6, brush B6, segment 167, wires 168 and 172, input of the device AD and thence to the right-hand terminal of the coil 7. Again, a circuit can be traced from the left-hand terminal of coil 6 over wires 164 and 40 45 165, segment 166, brush B6, segment 169 with the brush advanced, segment 170 of the commutator C8, brush B8, any one of the successive segments of the commutator C8, a respective network of contacts governed by the auxiliary brake 50 controlling mechanism as will be readily understood by an inspection of Fig. 9, wire 171, generator G and to the right-hand terminal of coil 7. It is clear from the foregoing that the coils 6 and 7 are connected with the input of the device 55 60 65 70 75 AD during the second one-half of a revolution of the rotor when brush B6 of the commutator C6 engages the segment 167, but that, during the first one-half of a revolution when the brush B6 spans the segment 169 they are successively connected with the generator G over the segments of the commutator C8 and a corresponding network of contacts of the brake controlling mechanism.

R2 is a direct current neutral relay which is energized in response to the synchronizing impulses sent out from the locomotive and is retained energized between the intervals of such impulses by current supplied over a stick circuit from a local source such as a battery 145. In order to energize the relay by a synchronizing impulse, the winding of the relay R2 is included in the output of the amplifier detector AD during the periods the brush B7 spans the segments 194 and 195, the circuit being traced from the lower 75 left-hand output terminal of device AD over

wire 224, front contact 173 of the relay R2, segment 174 of commutator C7, brush B7, segment 194 or 195, wire 223, winding of the relay R2 and wire 175 to the upper left-hand output terminal of the device AD. The stick circuit for the relay R2 includes the B terminal of battery 145, segment 186 of the commutator C9, brush B9, segment 187, front contact 188, wire 223, winding of the relay R2 and the opposite terminal C of battery 145. It is to be noted that the segment 187 is provided with two breaks 190 and 191, and, consequently, this stick circuit is ruptured twice for short intervals during each revolution of the rotor, and the relay R2 is released unless synchronizing impulses are received during the period the brush B7 spans the segment 194 and 195 and connects the winding of the relay R2 with the output of the device AD, the brush B7 spanning the segments 194 and 195 during the periods the brush B9 passes over the breaks 190 and 191.

146, 147, 148 and 149 constitute a system of planetary gears, by means of which the rotor shaft 144 is rotated and kept in synchronism with the rotor 114 on the locomotive. 153 is a relay which is operated by a synchronizing impulse which comes in from the locomotive at the start of each revolution of the rotor. The relay 153 in turn energizes an electromagnet 151 when the caboose 30 35 40 45 50 55 60 65 70 75 80 85 90 95 100 105 110 115 120 125 130 135 140 145 150 155 160 165 170 175 180 185 190 195 200 205 desired to establish the running condition of the auxiliary brake controlling mechanism. Referring first to the locomotive apparatus, when the brush B2 engages the segment 143 an impulse of current is supplied to the traffic rails, since the coils 4 and 5 are connected with the generator G as explained hereinbefore. This current impulse induces an electromotive force in the coils 6 and 7 of the caboose apparatus and an impulse flows in the input of the amplifier detector AD over the circuit including wire 164, back contact 177 of the relay R2 and wire 172 with the result that a corresponding impulse flows in the output of the amplifier detector AD over wire 224, back contact 178 of relay R2, winding of the relay 153 and wire 175 back to the device AD, and the relay 153 is energized. If the caboose rotor is behind the locomotive rotor, current flows from the B terminal of the battery 145 over front contact 179 of relay 153, segment 180 of commutator C5, brush B5, segment 181, since the rotor 144 is behind, back contact 182 of the magnet 152, winding of magnet 151 and to the opposite terminal C of the battery 145, and magnet 151 is energized to accelerate the rotor 144 in the manner previously described. If the caboose rotor 144 is ahead of the locomotive rotor then current flows from the B terminal of the battery 145 over front contact 179 of relay 153, segment 180, brush B5, segment 183 and winding of the magnet 152 and to the opposite battery terminal C and that magnet is energized to retard the rotor 144 in the manner previously described. The magnet 152 is provided with a stick contact 184 for retaining that magnet energized until the relay 153 is released, and false energization of the magnet 151, if brush B5 engages the segment 181 before relay 153 is released, is avoided. The next time brush B2 engages the segment 143 another impulse is sent out from the locomotive and the process is repeated until the caboose rotor 144 is brought into synchronism with the locomotive rotor 144. With the rotors synchronized the brush B5 engages the segment 185 during the reception of the synchronizing impulse, and the relay R2 is energized by a circuit that includes the front contact 179 of the relay 153, segment 180 of the commutator C5, brush B5, segment 185, wire 223, winding of the relay R2 and the C terminal of battery 145. With the relay R2 picked up in response to the synchronizing impulse, it is then retained energized by current from the battery 145 over the stick circuit previously traced, which includes its own front contact 188, and the segment 187 of the commutator C9.

With the rotors in synchronism and just after the start of the next rotation, brush B8 engages the segment 201, and an indication synchronizing impulse is supplied to the traffic rails by the caboose apparatus, the generator G being connected with the coils 6 and 7 over front contact 232 of the relay R2, segment 201, brush B8, segment 170, segment 169 of the commutator C6, brush B6, segment 166, wires 164 and 165, and coils 6 and 7 to the opposite terminal of the generator G. This impulse sent from the caboose induces an electromotive force in the coils 4 and 5 on the locomotive and is effective to cause an impulse to flow in the output of the amplifier detector AD for energizing the relay R1, the circuit being completed at the segment 135 of the commutator C3, since the brush B3 engages the segment 135 just at the start of a rotation. With the relay R1 picked up, it is then retained energized over its stick circuit which includes the segment 138 of the commutator C4. With the rotors operating in synchronism and the relays R1 and R2 both picked up, the next time the brush B2 engages the segment 124 a control impulse is supplied to the traffic rails, since the handle 3 is set at the running position. This control impulse appears at the caboose and induces an electromotive force in coils 6 and 7 during the interval that the brush B7 engages the segment 196 with the result that the impulse caused to flow in the output of the amplifier detector AD is supplied over wire 224, front contact 173 of relay R2, segment 174, brush B7, segment 196, winding of the magnet 192 of the valve D^R, winding of the magnet 193 of the valve D^S, and to the terminal C, and thence by wire 175 to the opposite output terminal of the device AD, and the valve D^R is opened, and the valve D^S is closed, to establish the running condition of the auxiliary brake controlling mechanism. When the valves D^R and D^S are operated, the respective contacts 198 and 199 controlled thereby are closed. As the rotor elements continue past the point where the brush B2 engages the segment 124 and the brush B7 engages its segment 196, the brush B2 successively passes over the segments 130 and 131 with a short break between, and two synchronizing impulses are sent out from the locomotive successively. When these two successive impulses appear at the caboose to induce electromotive forces in the coils 6 and 7, two successive impulses are supplied over the output of the device AD, which impulses flow along wire 224, front contact 173, segment 174, brush B7, segments 194 and 195 as the case may be, wire 223, winding of the relay R2 and wire 175 back to the device AD, and the relay R2 is retained energized during the intervals that the brush B9 passes over the breaks 190 and 191 in the segment 187 and ruptures the stick circuit for that relay. Immediately following the sending of these two synchronizing impulses, the brush B2 again engages the segment 143 and the locomotive apparatus sends out the usual synchronizing impulse which induces an electromotive force in the caboose coils 6 and 7 for energizing the input of its receiving apparatus. If the relay R2 is retained energized as a result of the two successive impulses just previously received nothing happens as the result of this last impulse. If the relay R2, however, is released due to the rotor 144 being out of synchronism then this last synchronizing impulse is effective to energize the relay 153 and either accelerate or decelerate the rotor 144 in the manner already explained. Assuming the relay R2 to have been held energized and the rotors to have started a new revolution in synchronism, then as the brush B8 engages the segment 201, the caboose apparatus supplies an indication synchronizing impulse for energizing the relay R1 on the locomotive, in the manner described above. As the brush B8 engages the segment 197 this time, a circuit is completed for supplying an indication impulse, the circuit extending from the right-hand terminal of the generator G over coils 6 and 7, wires 164 and 165, segment 166, brush B6, segment 169, segment 170 of the commutator C8, brush B3, segment 197, wire 200, network of contacts including front contacts 199 and 198 of valves D^S and D^R, respectively, wire 171 and to the opposite terminal of the generator G. When this indication impulse appears at the locomotive and induces an electromotive force in its coils 4 and 70

5, and a corresponding impulse is set up in the output of the associated device AD, this impulse flows over the circuit including the segment 156 of commutator C3 and the lamp LR since the segment 156 of the commutator C3 is spaced the same distance from the starting point as the segment 197 of the commutator C8. It follows that lamp LR is flashed to indicate to the locomotive operator the running condition of the caboose apparatus and the relay 141 is energized to close the valve 213. When the brush B2 again engages the segment 124 another control impulse is sent out from the locomotive which appears at the caboose for supplying the magnets 192 and 193 with an impulse for retaining them energized, and then as the rotors continue in the counter-clockwise direction the series of synchronizing impulses are repeated in the manner already described. As long as the valve handle 3 remains set in the running position this alternating exchange of control, indication and synchronizing impulses is effected in response to the rotation of the rotor elements. It is apparent that with the valve handle 3 set in any of the other operating positions, except the service position, a similar operation of the apparatus of Figs. 8 and 9 is obtained. In the service position no control impulses are sent out from the locomotive and the valve magnets on the caboose are all deenergized to establish the service condition of the auxiliary brake mechanism. No return indication impulses are now sent from the caboose. The synchronizing impulses are still exchanged by the two rotors during the service positions, since the synchronizing impulses are not controlled by the position of the engineer's brake valve.

To send a signal from the locomotive, the operator depresses the push button 132 to complete a transmitting circuit for connecting the generator G with the coils 4 and 5 during the interval the brush B2 engages the segment 189. During this same interval the brush B7 of the commutator C7 engages the segment 203 and a signal device 150 is energized, in response to this signaling impulse sent out from the locomotive. To signal from the caboose the operator depresses the push button 204 to complete a transmitting circuit during the interval the brush B8 engages the segment 205. This signaling impulse appears at the locomotive for inducing an electro-motive force in the coils 4 and 5 during the interval the brush B3 engages the segment 206 and the signal lamp 134 is illuminated in response thereto.

Although we have herein shown and described only two forms of apparatus embodying our invention, it is understood that various changes and modifications may be made therein within the scope of the appended claims without departing from the spirit and scope of our invention.

Having thus described our invention, what we claim is:

65 1. In a railway train brake control system comprising the usual engineer's brake valve on the locomotive, an auxiliary brake controlling mechanism capable of reproducing a given function of the engineer's valve on another vehicle 70 of the train, a source of current and a communication channel between the two locations; the combination with the above instrumentalities of a motor driven contact controlling element at each location each having a similar operating 75 cycle, synchronizing means partly at each loca-

tion operative to transmit current impulses between the two locations for starting an operating cycle of said elements substantially simultaneously, said means including a contact of the locomotive element closed only at the starting point of its cycle and a magnet on the other vehicle effective when energized to retard or advance its element to the starting point, and control means partly at each location governed by the engineer's brake valve operative to transmit 10 current impulses from the locomotive to the other vehicle for causing the auxiliary mechanism to establish said given function, said control means including a contact of each element each of which contacts is effectively operated at 15 the same predetermined time interval as measured from the starting point of the operating cycle.

2. In a railway train brake control system comprising the usual engineer's brake valve on 20 the locomotive, an auxiliary brake controlling mechanism capable of reproducing a given function of the engineer's valve on another vehicle of the train, a source of current, a communication channel between the two locations and an 25 indicating device on the locomotive; the combination with the above instrumentalities of a motor driven contact controlling element at each location each having a similar operating cycle, synchronizing means partly at each location operative to transmit current impulses between the two locations for starting an operating cycle of 30 said elements substantially simultaneously, said means including a contact of the locomotive element closed only at the starting point of its cycle 35 and a magnet on the vehicle effective when energized to retard or advance its element to the starting point, control means partly at each location governed by the engineer's brake valve operative to transmit current impulses from the locomotive to the other vehicle for causing the auxiliary mechanism to establish said given function, 40 said control means including a contact of each element each of which contacts is effectively operated at the same predetermined time interval as measured from the starting point of the operating cycle, and indication means partly at each location governed by the auxiliary mechanism operative to transmit current impulses from the vehicle for actuating the indicating device, said 45 indication means including a contact of each element each of which contacts is effectively operated at the same predetermined time interval as measured from the starting point of the operating cycle but which is different from the first 50 mentioned interval.

3. In a railway train brake control system comprising a source of air pressure and an auxiliary brake controlling mechanism capable of reproducing the functions of the usual engineer's brake valve on the locomotive on another vehicle of the train, a source of current at each location, a communication channel between the two locations and an indicating device on the locomotive; the combination with the above instrumentalities of a motor driven contact controlling rotor at each location, synchronizing means partly at each location operative to transmit current from the locomotive to the other vehicle at the start of a revolution of the locomotive rotor for bringing the other rotor to the starting point of a revolution and including a contact of the locomotive rotor closed only at the start of its revolution and a magnet on the other vehicle effective when energized to advance or retard its rotor to 75

- the starting point of a revolution, control means partly at each location governed by the position of the engineer's brake valve operative to transmit current from the locomotive for causing the 5 auxiliary mechanism to register with the engineer's valve and including a contact of each rotor each of which contacts is closed only at a predetermined distance from the starting point of a revolution of its rotor, and indication means 10 partly at each location governed by the auxiliary mechanism operative to transmit current from said other vehicle for actuating the indicating device and including a contact of each rotor each of which contacts is closed only at a second predetermined distance from the starting point of a revolution of its rotor.
4. In a railway train brake control system comprising a source of air pressure and an auxiliary brake controlling mechanism capable of reproducing 15 the functions of the usual engineer's brake valve on the locomotive on another vehicle of the train, a source of current at each location, a communication channel between the two locations and an indicating device on the locomotive; the combination with the above instrumentalities of a motor driven contact controlling element at each location each having a similar operating cycle with a given starting point, a first synchronizing means partly at each location operative to transmit current from the locomotive to the other vehicle for starting an operating cycle of the element on said other vehicle substantially simultaneously with the start of a cycle of the locomotive element and including 20 a contact of the locomotive element closed only at the starting point and a magnet on the other vehicle effective when energized to retard or advance its element to the starting point, a second synchronizing means partly at each location operative to transmit current from said other vehicle for energizing a control relay on the locomotive and including a contact of each element effectively operated a predetermined interval from the starting point, control means 25 partly at each location governed by the engineer's brake valve operative to transmit current from the locomotive for causing the auxiliary mechanism to register with the engineer's brake valve and including a contact of said relay and a contact of each element each of which element contacts is effectively operated a second predetermined interval from the starting point, and indication means partly at each location governed by the auxiliary mechanism operative 30 to transmit current from said other vehicle for actuating the indicating device and including a contact of each element each of which contacts is effectively operated a third predetermined interval from the starting point.
5. In a railway train brake control system comprising a source of air pressure and an auxiliary brake controlling mechanism capable of reproducing the functions of the usual engineer's brake valve on the locomotive on another vehicle of the train, a source of current at each location, a communication channel between the two locations and an indicating device on the locomotive, a contact controlling rotating member at each location, synchronizing means partly at each location operative to transmit current from the locomotive for causing the member at said other location to rotate in synchronism with the locomotive member, said means including a contact of the locomotive member closed at a predetermined point of each rotation and a magnet 40 on said other vehicle effective when energized to advance or retard its member to a point in the rotation which corresponds to the predetermined point of the locomotive member, control means partly at each location governed by the engineer's brake valve for causing the auxiliary brake controlling mechanism to register with the engineer's valve, said control means including a particular contact of each member for each of the different functions and which contacts are successively operated by the members with the two contacts of each respective function operated at substantially the same time as measured from said predetermined point, and indication means partly at each location governed by the auxiliary mechanism for actuating the indicating device, said indication means including a particular contact for each member for each of the different functions and which contacts are successively operated by the members with the two contacts of each respective function operated at substantially the same time as measured from said predetermined point.
6. In a railway train brake control system comprising the usual engineer's brake valve on the locomotive, an auxiliary brake controlling mechanism capable of reproducing the functions of the engineer's valve on another vehicle of the train, a current source and a communication channel between the two locations; the combination with the above instrumentalities of a rotating shaft at each location each of which is provided with a disc for each of the different functions, synchronizing means partly in each location for transmitting a current impulse from the locomotive at the start of each revolution of the locomotive shaft for bringing the shaft on said other vehicle to the start of its revolution, said means including a contact operated by the locomotive shaft and a magnet on the other vehicle effective when energized to advance or retard its shaft to the starting point, coding contacts operated by the discs of the locomotive shaft successively closed at predetermined points as measured from the starting point of a revolution, decoding contact mechanism for each disc of the shaft of said other vehicle, including a spring member normally biased to have its free end adjacent one side of the disc and adaptable of being actuated through a slot in the rim of the disc to the other side for closing the contact, a member associated with all the decoding contact mechanisms capable of longitudinal movement parallel with the shaft effective to actuate a spring when said spring aligns with the slot of its disc, means including a magnet for operating said member, control means governed by the engineer's brake valve to transmit a current impulse each revolution of the locomotive shaft when the contact of the disc corresponding to the position of the valve is closed for energizing said magnet on the other vehicle to close the corresponding decoding contact, and means controlled by the decoding contacts for causing the auxiliary mechanism to register with the engineer's valve.
7. In a control system comprising a contact assembly having different positions and located at one location, a controlled mechanism having different functions corresponding to the different positions of said assembly and located at another location, a current source and a communication circuit between the two locations; the combination with the above instrumentalities of a rotating shaft at each location each of which is

provided with a disc for each of said different positions, synchronizing means partly at each location for transmitting a current impulse from said one location at the start of each revolution of the shaft at said one location for bringing the shaft at said other location to the start of its revolution, said means including a contact operated by the shaft at said one location and a magnet at the other location effective when energized to advance or retard its shaft to the starting point of a revolution, coding contacts operated by the discs of the shaft at said one location and successively closed at predetermined points from the starting point of a revolution, decoding contact mechanism for each disc of the shaft at said other location including a spring member biased to have its free end adjacent one side of the disc and adaptable of being actuated through a slot in the rim of the disc to the other side of the disc for closing the contact, a member associated with all the decoding contact mechanisms capable of longitudinal movement parallel with the shaft and effective to actuate a spring when said spring aligns with the slot of its disc, a magnet effective when energized to operate said member, control means governed by the assembly to transmit a current impulse each revolution of the shaft at said one location when the contact of the disc corresponding to the position of the assembly is closed for energizing said magnet to close the contact of the corresponding decoding mechanism, and means controlled by the decoding contacts for causing the controlled mechanism to register with the position of the assembly.

8. In a railway train brake control system comprising a manually operated control device and an indicator on one vehicle of a train, a brake controlling mechanism capable of establishing a given function of the train brakes on another vehicle of the train, a current source and a communication circuit between the two vehicles; in combination with the above instrumentalities, a motor driven disc on each vehicle each having a given starting point and each provided with a cam lobe and a slot, the cam lobe and slot of one disc spaced from the starting point the same distances as the slot and cam lobe of the other disc, respectively, a decoding contact mechanism for each disc each including a spring member biased to have its free end adjacent one side of the disc and adaptable of being actuated through the slot to the other side of the disc for closing the decoding contact, a decoding magnet for each decoding contact mechanism effective when energized to actuate the spring, a normally open control contact for each disc but closed when engaged by the cam lobe, synchronizing means partly on each vehicle for transmitting a current impulse from said one vehicle at the start of each revolution of its disc for bringing the disc on the other vehicle to its starting point, said means including a contact operated by the control disc rotor and a magnet on the other vehicle effective when energized to advance or retard its disc to the starting point, means governed by the control device to transmit a current impulse each closing of the control contact of the disc on said one vehicle for energizing the decoding magnet on said other vehicle, a circuit governed by the decoding contact of said other vehicle for operating the brake controlling mechanism to said given function, means governed by said brake mechanism to transmit a current impulse each closing of the

control contact of the disc on said other vehicle for energizing the decoding magnet on said one vehicle and a circuit governed by the decoding contact on said one vehicle for actuating the indicator.

5

9. In a railway train brake control system comprising the usual engineer's brake valve on the locomotive, an auxiliary brake controlling mechanism capable of reproducing a given function of the engineer's valve on another vehicle of the train, a source of current and a communication channel between the two locations; the combination with the above instrumentalities of a first circuit controlling element having a cyclic movement on the locomotive, a first motor to drive said element at a given rate, a second circuit controlling element having a similar cyclic movement on said other vehicle, a second motor to drive said second element, means controlled by the first element at the start of each of its movements to transmit a synchronizing impulse, synchronizing means at the auxiliary mechanism responsive to such impulse to retard or advance said second element to the starting point of its movement, means governed by the second element in response to such retarding and advancing of the second element for varying the speed of said second motor, and control means governed by the engineer's valve and including a contact of each of said elements operative to transmit a control impulse each cycle of the elements for causing the auxiliary mechanism to reproduce said given function.

10. In a railway train brake control system comprising the usual engineer's brake valve on the locomotive, an auxiliary brake controlling mechanism capable of reproducing a given function of the engineer's valve on another vehicle of the train, a source of current and a communication channel between the two locations; the combination with the above instrumentalities of a first shaft on the locomotive, a first motor to rotate said shaft at a given speed, a second shaft on said other vehicle, a second motor to rotate said second shaft, means governed by the first shaft at the start of each revolution to transmit a synchronizing impulse, synchronizing means at the other vehicle responsive to such impulse to retard or advance the second shaft to the start of a revolution, means governed by the second shaft in response to such retarding and advancing for varying the speed of said second motor, and control means governed by the engineer's valve and including two contacts one operated by each shaft effective to transmit a control impulse each revolution of the shafts for causing the auxiliary mechanism to reproduce said given function.

11. A control system comprising two rotating shafts one at each of a first and a second location, a disc mounted on the shaft at said second location for rotation therewith, synchronizing means partly at each location for transmitting a current impulse from the first location at the start of each revolution of its shaft for bringing the shaft at the second location to the starting point of its revolution, said means including a contact operated by the shaft at said first location and a magnet at the second location effective when energized to advance or retard its shaft to the starting point, coding mechanism including a contact operated by the shaft at the first location and closed only at a predetermined distance from the starting point of a revolution, decoding mechanism at the second location includ-

60
